Primary Examiner — Derrick Holland*Assistant Examiner* — Lauren Calve*(74) Attorney, Agent, or Firm* — Timothy J. Klima; Shuttleworth & Ingersoll, PLC**CLAIM**

The ornamental design for a tea caddy, as shown and described.

DESCRIPTION

FIG. 1 is a perspective view of a tea caddy according to a first embodiment showing our new design;

FIG. 2 is a second perspective view thereof, shown in an open configuration;

FIG. 3 is a perspective view of a tea caddy according to second embodiment; and,

FIG. 4 is a second perspective view thereof, shown in an open configuration.

The broken lines shown represent unclaimed subject matter and form no part of the claimed design.

1 Claim, 2 Drawing Sheets
